PULSE GENERATING CIRCUIT

This invention relates to pulse generating circuits and more particularly to improvements relating to monostable multivibrators, nonstable multivibrators and blocking oscillators. In as much as the self-running period of conventional astable multivibrators, astable multivibrators and blocking oscillators varies dependent upon the variations in the source voltage and variations of ambient temperatures it is impossible to produce pulses of accurate waveform. Further when these devices are employed as frequency dividers it has been impossible to provide a large ratio of frequency division.

One object of this invention is to provide a new and novel pulse generating circuit which is not affected by the variations in the source voltage and ambient temperature by mere incorporation of a simple circuit element.

Another object of this invention is to provide a temperature compensated monostable multivibrator capable of operating independently of the variation in the ambient temperature by a unique utilization of a temperature sensitive element.

Still another object of this invention is to provide a novel temperature compensated astable multivibrator capable of operating independently of the variation in the ambient temperature by a unique utilization of a temperature responsive element.

A further object of this invention is to provide a novel voltage and temperature compensated monostable multivibrator capable of operating independently of the variation in the source voltage and ambient temperature by a unique utilization of an element whose current-voltage characteristic varies exponentially.

A further object of this invention is to provide a novel voltage and temperature compensated astable multivibrator capable of operating independently of the variation of the source voltage and ambient temperature by a unique utilization of an element whose current-voltage characteristic varies exponentially.

Still a further object of this invention is to provide a novel voltage and temperature compensated blocking oscillator capable of operating independently of the variation in the source voltage and ambient temperature by a unique utilization of an element whose current voltage characteristic varies exponentially.

Yet another object of this invention is to provide an efficient voltage and temperature compensated monostable multivibrator, nonstable multivibrator or a blocking oscillator by utilizing a temperature sensitive element and an element having an exponential current-voltage characteristic.

Further objects and advantages of the present invention will become apparent and this invention will be better understood from the following description, reference being made to the accompanying drawing. The features of novelty which characterize the invention are set forth in the appended claims.

In the drawing:

FIG. 1 is a circuit diagram of a conventional monostable multivibrator;

FIG. 2 is a circuit diagram of one example of a monostable multivibrator embodying this invention and utilizing a temperature sensitive element;

FIG. 3 shows diagrams to explain the temperature sensitive element to be employed in this invention;

FIG. 4 is a graph to compare the oscillating frequency variation ratio (percent) of a conventional monostable multivibrator and a novel monostable multivibrator;

FIG. 5 shows a connection diagram of one example of an astable multivibrator embodying this invention;

FIG. 6 shows a connection diagram of a modified monostable multivibrator of this invention;

FIG. 7 shows a connection diagram of a modified monostable multivibrator;

FIG. 8 shows a connection diagram of a monostable multivibrator utilizing a diode;

FIG. 9 shows a graph to show current viz, emitter-collector voltage characteristic of the transistor.

FIG. 10 shows forward current characteristics of a diode at various ambient temperatures;

FIG. 11 shows the operation of the circuit shown in FIG. 8;

FIG. 13 is a connection diagram of a blocking oscillator and FIG. 14 shows a monostable multivibrator utilizing both a temperature sensitive element and a diode.

FIG. 1 of the accompanying drawing illustrates a typical conventional monostable multivibrator employing transistors which are connected such that the base current of a transistor Tr1 flows through a resistor R3 whereas the collector current of a transistor Tr2 flows through resistors R1 and R2. As is well known in the art the self-running period of this circuit (the period in which the transistor Tr1 is in the off state) is given by the following equation (1)

$$T_1 = R_3 \times C \ln \frac{V_A + V_B - V_{EB}, (ON) - V_{CE2}(ON)}{V_B - V_{EB1}(ON)} - I_{C2}(OFF) \times R_2 \quad (1)$$

where V_A represents the source voltage applied to the collector electrodes of transistors Tr1 and Tr2 respectively through resistors R1 and R2, V_B the source voltage applied to the base electrode of the transistor Tr1 through the resistor R3, $V_{CE2}(ON)$ a voltage between emitter and collector electrodes of transistor Tr2 when it is conductive, $V_{EB1}(ON)$ a voltage between emitter and base electrodes of the transistor Tr1 when it is conductive, and $I_{C2}(OFF)$ the collector current of the transistor Tr2 when it is nonconductive.

Variation in the self-running period caused by the variation in the ambient temperature will now be considered under the assumption that source voltages V_A and V_B in equation (1) are constant. First the logarithmic term in equation (1) is assumed to be constant. Then the logarithmic term will be represented by equation (2)

$$\frac{V_A + V_B - V_{EB1}(ON) - V_{CE2}(ON) - I_{C2}(OFF) \times R_2}{V_B - V_{EB}(ON)} = K \quad (\text{constant}) \quad (2)$$

By solving equation (2) with respect to V_B , we obtain

$$V_B = \frac{V_A}{K-1} + V_{EB1}(ON) - \frac{V_{CE2}(ON) + I_{C2}(OFF)}{K-1} \quad (3)$$

Generally the multivibrator is operated by assuming that $K=2$, so that by substituting in equation (3) a set value of $K=2$ we obtain

$$V_B = V_A + V_{EB1}(ON) - V_{CE2}(ON) - I_{C2}(OFF) \times K_2 = V_A + V_1$$

where $V_1 = V_{EB1}(ON) - V_{CE2}(ON) - I_{C2}(OFF) \times R_2$

Accordingly in order to compensate for variations in $V_{EB1}(ON)$, $V_{CE2}(ON)$ and $I_{C2}(OFF)$ caused by the variation in ambient temperatures it is sufficient to select values of V_B and V_A that can satisfy equation (4). It will be clearly noted that the logarithmic term is made constant by such selection.

Next the term $R_3 \times C$ in equation (1) will be considered. The temperature coefficient of $R_3 \times C$ is given by the sum of the respective temperature coefficients of resistor R3 and condenser C and the temperature variation component of $R_3 \times C$ can be compensated for by maintaining voltages V_B and V_A in the logarithmic term at a definite relation. Thus, by setting the relation between voltages V_B and V_A to the relation of

$$V_B = V_A + V_0 \quad (5)$$

and then by varying V_0 , it is able to compensate for the temperature variation component of $R_3 \times C$. V_0 in equation (5) is set to a value represented by the following equation (6)

$$V_0 = V_1 + V_2 \quad (6)$$

where V_2 represents a voltage adapted to compensate for the temperature variation component of $C \times R_3$. Thus it will be clearly noted that the variable component of the logarithmic term as well as the variable component of $R_3 \times C$ in equation (1) caused by the variation in the ambient temperature can be compensated for by applying a voltage $V_B = V_A + V_0$ to the base electrode of transistor Tr1 in FIG. 1 and by causing V_0 to vary in response to temperature variation.

As a means for causing V_0 to vary in response to temperature variation, compensation circuits including a temperature sensitive element 1 such as a thermistor or posistor as in-

bodiment of a monostable multivibrator employing such a compensation circuit. In the embodiment shown in FIG. 2 a thermistor T_h is employed as the temperature sensitive element. As is obvious to those skilled in the art a thermistor or a posistor is to be selected as the temperature sensitive element dependent upon whether the temperature coefficient of the compensation voltage V_0 is positive or negative.

FIG. 4 shows the result of experiment made on the monostable multivibrator shown in FIG. 2 wherein a temperature sensitive element is used to compensate for the variation in the self-running period. Fig. 4 shows that, where the source voltage $V_{cc}=3.0$ volts and the ambient temperature ranged from -20° to $+60^\circ$ C. the oscillating frequency variation of the conventional monostable multivibrator shown in FIG. 1 was 15 percent as shown by a curve *a* whereas that of the novel monostable multivibrator as shown in FIG. 2 was only 2 percent as shown by a curve *b*.

FIG. 5 illustrates a blocking oscillator embodying this invention and utilizing a temperature sensitive element 1. As is well known the self-running period of a well-known blocking oscillator not embodying this invention is shown by

$$T = (C_1 + R_3 + C_2) \times R_4 \ln \left[\frac{V_A + V_B - V_{EB1}(ON) - V_{CE1}(ON)}{V_B - V_{EB1}(ON)} \right] - I_{C2(OFF)} \times R_2 \quad (7)$$

Accordingly the compensating function of the oscillator shown in FIG. 5 for the variation in the ambient temperature afforded by the temperature sensitive element 1 is the same as that of the case of said monostable multivibrator.

Further, to attain the same object, according to this invention the temperature sensitive element 1 may be connected in parallel with a series circuit comprising a collector resistor R_2 and the transistor T_{r2} , as shown in FIG. 6 or in series with the base resistor R_3 , as shown in FIG. 7.

A novel temperature and voltage compensated pulse generating circuit according to this invention which is not affected by the variations in the supply voltage and ambient temperature will now be described hereunder. In said equation (1) which generally represents the self-running period of the circuit shown in FIG. 1, the variation in the self-running period caused by the variation in the source voltage will first be analyzed by assuming that the ambient temperature is constant. In the logarithmic term of equation (1) when voltages V_A and V_B vary, values of $V_{EB1}(ON)$, $V_{CE2}(ON)$ and $I_{C2(OFF)}$ do not vary linearly. $I_{C2(OFF)} \times R_2$ becomes a constant voltage and voltages $V_{EB1}(ON)$ and $V_{CE2}(ON)$ manifest an exponential current-voltage characteristic as shown in FIG. 9 with respect to the base current of transistor T_{r1} and to the collector current of transistor T_{r2} . As a consequence the logarithmic term of equation (1) would not become constant for varying voltages V_A and V_B even if voltages V_A and V_B vary proportionally. For this reason the self-running period T_1 would vary. In order to make constant the self-running period T_1 , voltages V_A and V_B must satisfy following equations (8) and (9).

$$V_B = V_A + V_{EB1}(ON) - V_{CE2}(ON) - I_{C2(OFF)} \times R_2 \quad (8)$$

$$\Delta V_B = \Delta V_A + \Delta V_{EB1}(ON) - \Delta V_{CE2}(ON) \quad (9)$$

In equation (9) symbol Δ represents increments of varying voltages V_A and V_B .

By substituting equation (8) in equation (1) we obtain the following equation representing the self-running period T_1

$$I_1 = R_3 \times C_{n2} \quad (10)$$

This equation means that the self-running period T_1 is independent of voltages V_A and V_B . A circuit that satisfies equations (8) and (9) is a circuit wherein a diode D is connected in series with collector resistors R_1 and R_2 of transistors T_{r1} and T_{r2} as shown in FIG. 8. In this figure if it is assumed that V_{cc} represents the source voltage and V_F represents the forward voltage of the diode D, then we obtain

$$V_{cc} = V_B = V_F \quad (11)$$

As is well known in the art the forward characteristic of the forward voltage V_F of diode D is an exponential current-voltage characteristic just like said voltage $V_{EB1}(ON)$.

Thus by selecting a forward voltage V_F which satisfies following equations (12) and (13) as the forward voltage of diode D it becomes possible to satisfy above described equations (7) and (8) so that equation (1) becomes equation (10) thus providing an extremely stable self-running period independent of the variation in the source voltage

$$V_F = V_{EB1}(ON) - V_{CE2}(ON) - I_{C2(OFF)} \times R_2 \quad (12)$$

$$\Delta V_F = V_{EB1}(ON) - \Delta V_{CE2}(ON) \quad (13)$$

The voltage V_F that can satisfy equation (11) can be provided by adjusting a resistor R_6 shown in FIG. 8 so as to control the forward current of diode D shown in FIG. 10. Where several stages of monostable multivibrators are used it is possible to obtain a voltage V_F that satisfies equation (12) by adjusting the forward current of diode D by means of the collector current and the like of monostable multivibrators other than that shown in FIG. 8. Condenser C_2 shown in FIG. 8 is a smoothing condenser.

Variation in the self-oscillating oscillating frequency caused by the variation in the ambient temperature will now be analyzed by assuming that voltages V_A and V_B in equation (1) are constant. In equation (1) the variation of the product $R_3 \times C$ caused by the variation in the ambient temperature can be made extremely small by the proper selection of respective temperature coefficients. As a consequence, when considering the logarithm of equation (1), even when voltages V_A and V_B are assumed constant, since $V_{EB1}(ON)$, $V_{CE2}(ON)$ and $I_{C2(OFF)} \times R_2$ vary, the logarithmic term also varies. Where the voltage V_B is maintained constant, it is able to make constant the self-running period by satisfying the following equation.

$$\Delta V_A = \Delta V_{EB1}(ON) - \Delta V_{CE2}(ON) - \Delta I_{C2(OFF)} \times R_2 \quad (13)$$

In equation (13) symbol Δ represents respective increments caused by the variation in the ambient temperature. Since the voltage ΔV_A in equation (13) coincides with the current-voltage characteristics of diode D shown in FIG. 10 which are plotted by taking the ambient temperature T_a as the parameter, it becomes possible to satisfy the following equation (14) by utilizing the variation ΔV_F of the forward voltage V_F of diode D caused by the variation in the ambient temperature.

$$\Delta V_F = \Delta V_{EB1}(ON) - \Delta V_{CE2}(ON) - \Delta I_{C2(OFF)} \times R_2 \quad (14)$$

Consequently equation (1) becomes independent of the ambient temperature whereby an extremely stable self-oscillating period can be provided.

As has been described in the foregoing, it is possible to maintain the self-running period at an extremely stable state irrespective of variations in source voltage and ambient temperature by utilizing the forward voltage of diode D connected in series with collector resistors R_1 and R_2 as shown in FIG. 8. One example of the operation of the circuit shown in FIG. 8 is plotted in FIG. 11 which shows a set of source voltage (V_{cc}) viz self-running period variation ratio (in percent) characteristics by taking ambient temperatures of -20° , $+25^\circ$ and $+60^\circ$ C. as the parameter. Within a range of source voltage of from 1.5 v. to 6.0 v., the self-running period variation ratio was about 30 percent without compensation (not employing this invention) but this ratio was decreased to about 2 percent with compensation (employing this invention). In FIG. 11 dotted line curves show characteristic curves without compensation whereas solid line curves those compensated in accordance with this invention.

Figs. 12 and 13 show circuits of an astable multivibrator and of a blocking oscillator, respectively, constructed according to this invention. The self-running period of the astable multivibrator is expressed by said equation (7). Thus, in order to make stable this self-running period, a diode D is connected as shown in FIG. 12 in quite the same manner as in the case of the monostable multivibrator shown in FIG. 8.

The operation of the blocking oscillator of this invention shown in FIG. 13 is as follows: In a well-known blocking oscillator not employing this invention, when the turns ratio of a transformer is selected 1: n the self-running period T of this oscillator can be shown by the following equation (15) as is well understood by those skilled in the art.

$$T_r = C \times R1 I_n \frac{\frac{1}{n}V_A + V_B - V_{EB}(ON) - \frac{1}{n}V_{CE}(ON)}{V_B - V_{EB}(ON)} \quad (15)$$

Accordingly, if following equations (16) and (18) were satisfied, the self-running period T_r shown by equation (15) would become quite stable.

$$V_B = V_A + V_{EB}(ON) - V_{CE}(ON) \quad (16)$$

$$\Delta V_B = \Delta V_A + \Delta V_{EB}(ON) - \Delta V_{CE}(ON) \quad (17)$$

Since equations (16) and (17) coincide with above described equations (7) and (8) respectively, it will be obvious that the same compensation function is provided for the circuit shown in FIG. 13.

FIG. 14 shows a modified monostable multivibrator according to this invention wherein the self-running period is made more stable by utilizing both a temperature sensitive element and a diode. Since the circuit of this embodiment corresponds to the combination of previous embodiments, it is believed unnecessary to describe its operation. It is of course to be understood that both a temperature sensitive element and a diode can be used in monostable multivibrators and blocking oscillators with equivalent results.

While in the above embodiments diodes were used as the 25

compensating element it should be understood that the invention is not limited to such particular elements but any element having a similar exponential current-voltage characteristic, such as thermistor, may be used.

It should be obvious that many alterations and modification may be made to the described embodiments without departing from the spirit and scope of the invention as defined in the appended claims.

What is claimed is:

- 10 1. In a blocking oscillator compensated for the variation in the source voltage and/or ambient temperature comprising:
a transistor;
a primary winding connected to the base electrode of said transistor;
- 15 a secondary winding electrically coupled with said primary winding and connected to the collector electrode of said transistor; and
a power source;
the improvement comprising:
a diode having exponential current-voltage characteristic and connected in the forward direction between said source and said secondary winding, said diode, power source and secondary winding forming a series circuit, said diode providing said compensation.
